UNITED STATES PATENT OFFICE.

HENRY J. DENGLER, OF ROCHESTER, NEW YORK.

ROLLER-SUPPORT.

No. 885,146.

Specification of Letters Patent.

Patented April 21, 1908.

Application filed August 12, 1907. Serial No. 388,132.

To all whom it may concern:

Be it known that I, HENRY J. DENGLER, of Rochester, in the county of Monroe and State of New York, have invented certain new and useful Improvements in Roller-Supports; and I do hereby declare the following to be a full, clear, and exact description of the same, reference being had to the accompanying drawings, forming a part 10 of the specification, and to the reference-numerals marked thereon.

The present invention which relates to roller supports of the type in which a roller is carried by adjustable bearings and is held 15 yieldingly against the work, has for an object to provide a construction which will enable the roller to operate with variable pressure without causing the yielding device to impose friction upon the roller adjusting device.

20 To this and other ends the invention consists in certain improvements and combinations of parts as will be hereinafter more fully described, the novel features being pointed out in the claims at the end of the 25 specification.

In the drawings: Figure 1 is a side view of a board printing machine embodying my invention. Fig. 2 is an end view of the same machine. Fig. 3 is a detail sectional view 30 through one embodiment of the roller support. Fig. 4 is a detail sectional view of another embodiment. Fig. 5 is a detail sectional view of still another embodiment.

Similar reference numerals in the several 35 figures indicate similar parts.

In some classes of machines, such as those for printing on boards, it is necessary to have a roller bear with great but yielding pressure on an article passing therebeneath. This 40 result has been effected heretofore in such a manner that the yielding devices have imposed a great deal of friction on devices which have been employed for adjusting the roller to permit the latter to operate on articles of other thicknesses. In the present invention I employ for the yielding devices a 45 stop which renders the device ineffective except when the roller is in operation, thus permitting the operation of the adjusting device 50 without imposing friction thereon.

While the invention is herein described and shown as embodied in a machine for printing on boards, it will be apparent that it is applicable to all other machines in which 55 similar results are obtained.

The board printing machine in this in-

stance comprises a bed or table 1 having a lower roller platen 2 journaled thereon and arranged vertically above this roller platen is a roller 3 which it is desirable to support 60 in the manner before mentioned. For this purpose the roller is mounted in bearings 4 vertically adjustable on guides 5 and raised and lowered by suitable adjusting devices, preferably in the form of a pair of vertical 65 screw shafts 6 operated by a horizontal shaft 6^a. The screws are movable slightly in an axial direction through their bearings which are in this instance in the form of horizontal arms 8 overhanging the bearings 4 and 70 flanges or collars 7 rest upon the upper surfaces of the arms 8 and support the roller.

The yielding devices are preferably in the form of yielding elements 80 surrounding the screws 6 and each having a movable abutment 9 at one end and an adjustable abutment 10 at the other end to vary the compression of the yielding element, the adjusting means preferably comprising a nut 11 which is held in its adjusted position by a 80 lock nut 12. The yielding devices are normally held away from the fixed abutments, which in this instance are the under faces of the bearings for the screw shafts 6, by a stop or shoulder 13, so that the screw shafts may 85 be rotated freely to adjust the roller without friction due to the pressure applying devices. When something passes beneath the roller the movable shafts carry the movable abutments and their stops 13 upwardly until the bearings or fixed abutments 8 are engaged by the movable abutments 9 when the latter are stopped to compress the yielding elements and apply pressure to the device under the roller. 95

In the embodiment of the invention shown in Figs. 1, 2 and 3, the stop is formed by providing one of the screw shafts 6 with an integral enlargement 13 which also acts as a bearing to turn in the arm or bearing 8. 100 This enlargement may also be in the form of a sleeve or bushing 13^a interposed between one of the movable abutments 9 and a flange 7, as shown in Fig. 4, and this sleeve may be provided with a flange at its lower end, arranged within a socket 15 in the bearing 8 and having an annular series of balls 16 supported thereon, as shown in Fig. 5. 105

From the foregoing it will be seen that I have provided a construction in which the 110 pressure on the roller may be varied without imposing any friction on the screw shafts, so

that less power will be required to adjust the roller vertically.

I claim as my invention:

1. The combination with a roller and an 5
adjustable bearing therefor, of an axially
movable rotary shaft for adjusting said bearing,
a fixed abutment, and a yielding device
carried by the shaft, and normally out of
engagement with the fixed abutment but
10 adapted to contact therewith, when the shaft
is moved axially.

2. The combination with a roller and an
adjustable bearing therefor, of an axially
movable rotary shaft for adjusting said bearing,
15 a fixed abutment, a yielding device carried
by the shaft, and a stop movable with
the shaft and arranged to prevent the yielding
device engaging the abutment except
upon the axial movement of the shaft to
20 carry the device to the abutment.

3. The combination with a roller and an
adjustable bearing therefor, of a rotary shaft
for adjusting said bearing, a bearing for the
shaft in which the latter is movable axially
25 and a yielding device normally out of engagement
with the bearing but adapted to coöperate
therewith when the shaft is moved
axially.

4. The combination with a roller and an
adjustable bearing therefor, of a rotary shaft
30 for adjusting said bearing, a bearing for the
shaft in which the latter is movable axially,
a yielding device normally out of engagement
with the bearing but adapted to coöper-
35 erate therewith when the shaft is moved
axially, and means for varying the compres-
sion of the yielding device.

5. In a roller support, the combination
with a roller and an adjustable bearing there-
40 for, of an axially movable rotary shaft for
adjusting said bearing, a fixed abutment, a
yielding device carried by the shaft, and nor-
mally out of engagement with the fixed abu-
45 ment but adapted to contact therewith
when the shaft is moved axially, and means
for varying the compression of the yielding
device.

6. The combination with a roller and an
adjustable bearing therefor, of a rotary shaft
for adjusting said bearing, a bearing for the 50
shaft in which the latter is movable axially,
a yielding device carried by the shaft adapted
to contact with the bearing, when the shaft
is moved axially, and a stop movable with
the shaft and normally holding the yielding 55
device away from the bearing.

7. The combination with a roller and an
adjustable bearing therefor, of a rotary shaft
for adjusting said bearing, a bearing for the
60 shaft in which the latter is movable axially,
a yielding device carried by the shaft adapted
to contact with the bearing, when the shaft
is moved axially, a stop movable with the
shaft and normally holding the yielding 65
device away from the bearing, and means for
varying the compression of the yielding
device.

8. The combination with a roller and an
adjustable bearing therefor, of an axially
movable rotary shaft for adjusting said bearing,
70 a fixed abutment, a yielding device carried
by the shaft, comprising a yielding ele-
ment and a movable abutment for coöperat-
ing with the fixed abutment, and a stop car-
ried by the shaft and coöperating with the 75
movable abutment to normally hold the lat-
ter out of contact with the fixed abutment.

9. The combination with a roller, of vertical
guides, bearings in which the rollers
turn movable on the guides, simultaneously
80 operable axially movable screw shafts con-
nected to the bearings, fixed abutments,
yielding elements surrounding the shafts be-
low the fixed abutments and having movable
abutments to coöperate with the fixed abu-
85 ments and stops on the shafts to engage the
movable abutments, permitting the movable
abutments to engage the fixed abutments
when the screw shafts move axially.

HENRY J. DENGLER.
